UNITED STATES PATENT OFFICE

CRAWFORD C. LOOMIS, OF ILLION, NEW YORK, ASSIGNOR TO REMINGTON ARMS COMPANY, INC., A CORPORATION OF DELAWARE

FIREARM

Application filed September 22, 1930. Serial No. 483,585.

This invention relates to firearms, and contemplates a novel shell rim engaging extractor intended primarily for the purpose of withdrawing fired shells from the chamber.

5 For the purpose of illustration, the invention is shown as applied to a firearm of the type described in the patent to Browning, No. 1,083,384, January 6, 1914. In guns of this type, a column of cartridges is stored 10 in a magazine tube which lies chiefly in the stock of the gun, its forward end projecting into the receiver and above the breech block. The breech block is supported and reciprocates upon a trigger plate, with which it is 15 assembled in a manner permitting its ready removal, and is retracted by the force of the recoil of the fired shell and, when so retracted, permits the foremost cartridge to descend until its head is engaged by the 20 upper portion of the front face of the breech block, whereby said cartridge is pushed into the chamber as the breech block goes forward to home position. After the firing of a cartridge the breech is retracted by the force of 25 the recoil and in this operation the fired shell is withdrawn from the chamber, owing to its engagement by an extractor device associated with the breech block. Since the breech is recoil operated the extractor must 30 have an ample surface in engagement with the rim and must firmly engage the rim in order to prevent the extractor from shearing through the rim or from moving to such a position as would disengage the cartridge 35 before it is clear of the chamber. As the breech block reaches its rearmost position, the shell held by the extractor is ejected downwardly, and at this time it is desirable that the extractor yield not only longitudinally but vertically in order to quickly free 40 the shell and permit its prompt ejection by the ejector devices.

It is an object of the present invention to provide an improved form of extractor 45 capable of both vertical and longitudinal movement.

It is a further object of the invention to retain such an extractor in its shell rim engaging position both vertically and horizontally 50 tally by means of a single spring.

It is a further object of the invention to provide an extractor having both vertical and longitudinal movement and comprising but a single element received by two supports and controlled by a single spring, said 55 spring being compressed either by a vertical or horizontal movement of the shell rim engaging part of the extractor.

It is a further object of the invention to utilize a part of the improved extractor as a 60 retaining device for the means by which the breech block is assembled with the trigger plate.

With these and other incidental objects in view, the invention consists in the novel devices and combinations of parts illustrated in the drawing and to be hereinafter more fully described.

In the drawing:

Fig. 1 is a fragmentary side elevation, partly in section, of a breech mechanism including an extractor according to the present invention.

Fig. 2 is a section on the line 2—2 of Fig. 1.

Fig. 3 is an enlarged elevation, partly in section, of the extractor of the present invention showing its mounting in the breech block.

Fig. 4 is a section substantially on the line 4—4 of Fig. 3.

Fig. 5 is an enlarged fragmentary sectional side elevation, showing the extractor in shell releasing position.

The firearm comprises a stock 10 and a receiver 11 which contains the breech and firing mechanisms and a part of the magazine, and has secured to its front end the usual chambered barrel (not shown). The foremost cartridge 12 in the magazine overlies the breech block and, when the breech is retracted, is moved forward and downward following the guide surface 13 into position to be engaged by the front face of the breech block 14 as said breech block moves forward to chamber closing position. The cartridge 15 in Fig. 1 is in the position with respect to the breech block which it occupies when in the chamber, the chamber having been omitted for greater clearness.

The extractor, indicated generally by the 100

numeral 16, is shown in front elevation in Fig. 2 and in side elevation in Fig. 1. Said extractor comprises a pair of upwardly extending fingers 17 for engagement with the rim of the cartridge, as shown in Fig. 1. It is of substantial depth lengthwise of the gun and is supported on an upper stud 18 and a lower stud 19, said studs being received respectively in an upper notch 20 and a lower notch 21. Said studs are supported in and extend transversely of the breech block. Said notches are both of greater width and greater depth than the diameter of the studs to permit the rocking and sliding movements of the extractor, to be presently described. A recess in the upwardly extending portion of the extractor receives a locating plunger 22 which is pressed downwardly by a spring 23, and has an arcuate head adapted to engage the cylindrical stud 19 in such a manner that the stud is not only held vertically, but is likewise cammed rearwardly. This mechanism is clearly illustrated in Fig. 3, in which it will be seen that the spring 23 serves both to elevate the extractor and to rock it clockwise about the stud 19, holding the shank 161 of the extractor in contact with the face of the breech block. With the extractor in this position, the rearward edge of the notch 20 is in engagement with the locating stud 18, thus increasing the resistance of the shell rim engaging fingers 17 to movement away from the breech block. The positive extraction of tightly fitting shells is thus insured.

As the breech block is retracted, the extractor holding the shell and carrying it along with the breech block, the upper part of the shell head is engaged by a suitable 40 ejector member, such as the abutment 24 (Fig. 1). The breech block continuing to move rearwardly, while the shell is stopped by the ejector, the shell is rotated counterclockwise substantially about the bottom of 45 the rim. In this movement the shell is quickly disengaged from the extractor, which is both shifted bodily downward and rocked about the upper locating stud 18, assuming the position shown in Fig. 5. The rocking 50 movement of the extractor, as well as its vertical movement, compresses the spring 23, since it moves the end of plunger 22 upwardly and rearwardly upon the cam pin 19 from the Fig. 3 position to the Fig. 5 position. As 55 soon as the shell is free from the fingers 17, spring 23 causes the extractor to resume the Fig. 3 position.

The breech block is received between and supported upon side plates 25 and 26 of the trigger plate. The forward end of the breech block is of reduced width, permitting the stud 18 to be provided with an under-cut head 27 by which the stud may be grasped with the fingers and withdrawn without the 65 use of tools. When the stud 18 is removed

the extractor assembly may be rocked about the stud 19 until its upper end is clear of the breech block and thereby removed.

The breech block is retained against undesirable upward movement relative to the trigger plate by suitable means which may comprise a plunger 28 received in a transverse slot in a downwardly extending finger piece 32 at the forward end of the breech block and thrust outwardly by suitable means such as a spring 29. In assembling the breech block with the trigger plate the plunger 28 is pressed inwardly and the lower part of the breech block is passed downward between the side pieces 25 and 26, after which plunger 28 moves outwardly below the side piece 26, thereby retaining the breech block in place.

Means must be provided for retaining the plunger 28 in its recess. According to the present invention, said means comprises a retaining stud 30 adapted to engage a section 31 of the plunger 28, which section is of reduced diameter. A recess for receiving the retaining stud 30 extends rearwardly and downwardly into the breech block finger piece 32 from a position adjacent the lower rearward portion 33 of the extractor. The part 33 of the extractor thus serves as a retaining device for the stud 30 and eliminates the necessity for using retaining screws or drive pins.

The particular device herein described and illustrated in the drawing is to be understood as merely a representative embodiment of inventions which may take a variety of other forms all falling within the scope of the appended claims.

What is claimed is:

1. In a firearm, a shell extractor, supporting means therefor proportioned and positioned to permit universal movement of the extractor in a single plane, and means including one spring only for controlling said universal movement.
2. In a firearm, a breech block, a shell extractor device comprising two slots, and two separate supporting and movement limiting means in said breech block engaging in said slots, said slots receiving said means with clearance in all directions therearound.
3. In a firearm, a breech block, a shell extractor comprising a pair of reversely facing slots and movement limiting means in said breech block engaging in said slots, the area of said slots being greater than the area of said means.
4. In a firearm, a breech block, a shell extractor comprising a slot, a stud in said breech block engaging in said slot, and a movement controlling device carried by said extractor and engaging the periphery of said stud.
5. In a firearm, a breech block, a shell extractor comprising a slot, a stud in said breech block engaging in said slot, a movement controlling device carried by said extractor

and engaging the periphery of said stud, and a second stud in said breech block engaging and limiting the movement of said extractor.

5 6. In a firearm, a breech block, a shell extractor comprising a pair of reversely facing slots, studs in said breech block engaging in said slots, said studs being of a diameter less than the length and width of
10 said slots, whereby movement of said extractor is permitted and limited.

15 7. In a firearm, a breech block, a shell extractor comprising a slot, a stud in said breech block engaging in said slot, and a
15 spring pressed plunger carried by said extractor and engaging the periphery of said stud.

20 8. In a firearm, a breech block, a shell extractor comprising a slot, a stud in said breech block engaging in said slot, a spring pressed plunger carried by said extractor and engaging the periphery of said stud, and a second stud in said breech block engaging and limiting the movement of said extractor.

25 9. In a firearm, a breech block, a shell extractor comprising a slot, a stud in said breech block engaging in said slot, a spring pressed plunger carried by said extractor and engaging the periphery of said stud,
30 and a second stud in said breech block engaging and limiting the movement of said extractor, said second stud being provided with a finger piece to facilitate its removal.

35 10. In a firearm, a breech block, a shell extractor associated with said breech block, a pair of extractor supporting studs in said breech block, one of said studs being removable, the construction and arrangement being such that upon the removal of said removable stud said extractor can be withdrawn from said breech block.

40 11. In a firearm, a trigger plate, a breech block supported thereon, means in said breech block for retaining said breech block
45 in said trigger plate, a shell extractor in said breech block, and means whereby said shell extractor secures said breech block retaining means in place.

50 12. In a firearm, a trigger plate, a breech block, a plunger in said breech block adapted to retain said breech block in said trigger plate, a plunger holding stud, and a shell extractor in said breech block having a part adapted to prevent displacement of said
55 plunger holding stud.

CRAWFORD C. LOOMIS.
